(57) **CLAIM**

The ornamental design for a handle for a hand tool, as shown and described.

DESCRIPTION

FIG. 1 is a perspective view of a handle for a hand tool, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the cover in an open condition.

The broken lines in the drawings illustrate features of the handle as well as environment that form no part of the claimed design.

1 Claim, 5 Drawing Sheets
